SHOE TREATING APPARATUS

Fred C. Eastman, Marblehead, Mass., assignor to
 United Shoe Machinery Corporation, Borough
 of Flemington, N. J., a corporation of New
 Jersey

Application December 15, 1939, Serial No. 309,433

9 Claims. (Cl. 12—1)

This invention relates to shoe-treating apparatus of the type in which heat and moist vapor are used to condition thermo-plastic toe-boxes and the lasting margins of pulled-over shoes about to be toe-lasted.

An object of the invention is to provide an improved apparatus in which the conditioning treatment may be accelerated without excessive heat, excessive vapor, or excessive waste of either. In former apparatus for this purpose heat and vapor far in excess of actual requirements are habitually supplied and the surplus vapor and much of the surplus heat are discharged into the atmosphere, and thus wasted.

The invention herein set forth is predicated upon recognition of the fact that the process of conditioning the materials of a shoe cannot be accelerated by supplying heat and vapor in excess of the natural rate of absorption which, in most cases, requires about one minute to produce satisfactory results. Speed is one of the principal objectives in all types of such apparatus and many of them supply quantities of heat and vapor so much in excess of the quantities actually absorbed by the work that various objectionable results are produced by the quantities wasted.

On the other hand, the present invention provides an apparatus in which the quantities of vapor and heat are restricted to minimize waste, and in which the conditioning process is accelerated by causing a small quantity of vapor diluted in a large quantity of heated air to impinge against the work while flowing at high velocity under forced draft.

The apparatus illustrated herein as embodying the novel features of the present invention provides a closed air-circuit including a treatment chamber through which heated air and moist vapor may be circulated without being emitted into the atmosphere outside the apparatus, and a power-driven blower located in the circuit to maintain circulation of the fluids at high velocity so long as treatment of work is required. The closed circuit also includes a heating chamber through which the vapor must pass at least once before it is used and through which it may flow repeatedly until used.

One of the problems due to the use of excessive quantities of moist vapor inside a casing is to prevent the shoes from being stained with condensate that accumulates on the interior surfaces of the walls of the treatment chamber and drips therefrom. The present invention avoids this problem as a result of diluting a small

quantity of vapor in a large quantity of heated air and circulating the mixture at a velocity high enough to insure rapid tempering of the work. Whatever moisture is not absorbed by the work is returned at high velocity to the heating chamber to be replenished with additional vapor and supplied again to the treatment chamber without undergoing the process of condensation.

The illustrated apparatus comprises thermo-insulated outer walls and heat-radiating inner walls. Both chambers are enclosed within the insulated walls but divided from each other by partition walls that radiate heat to both chambers, the source or sources of heat being localized in a hollow inner wall in the heating chamber from which the heat is transferred to the treatment chamber partly by convection and partly by conduction and radiation.

The vapor is supplied to the air-stream through a duct in the aforesaid hollow wall which, by reason of containing the source of heat, is the hottest wall in the air-circuit and insures high temperature of both the air and the vapor at the point where they are mixed.

Referring to the drawing,

Fig. 1 is a front elevation of a shoe-treating apparatus embodying the novel features of the present invention;

Fig. 2 is a horizontal section through the casing of the air-circuit in the plane indicated by line II—II in Fig. 1;

Fig. 3 is a side elevation, partly broken away and partly in section, of the apparatus shown in Fig. 1; and

Fig. 4 is a top plan view of a fragment of a partition wall having louvers through which the air-stream and the moist vapor enter the treatment chamber under and in register with the forepart of a shoe inserted for treatment.

The air-circuit of the apparatus is enclosed in a casing comprising a front wall 10, a rear wall 11, top walls 12 and 13, two sections 14 and 15 of a bottom wall, a side wall 16, and two sections 17 and 18 constituting the opposite side wall. These walls are all outer walls. The walls 10, 11, 12, 14, 16 and 17 are fabricated from confronting plates of sheet metal between which thermo-insulating material is packed. The walls 13, 15 and 18 are integral components of a cast metal heat-radiating member that also includes a vertical partition 20 (Fig. 3), a horizontal partition 21, a vertical web 22 connecting the portions 15 and 21, and two groups of baffle-pins 23 projecting from opposite faces of the web.

The treatment chamber 25 is bounded by the front wall 10, the side walls 16 and 17, the top wall 12, the vertical partition 20 that constitutes its rear wall, the horizontal partition 21 that constitutes a portion of its bottom wall, and a sheet metal partition 24 connecting the partition 21, the front wall 10 and the side walls 16 and 17. The front wall of the treatment chamber is provided with two shoe-receiving openings 26 and the rear wall thereof is provided with a circular outlet port 27 for circulation of an air-stream.

The heating chamber is bounded by the front wall 10, the rear wall 11, the bottom wall 14, 15, the side walls 16, 17 and 18, the partitions 20 and 24, and the top wall 13. The wall 13 is curved to provide a stream-lined cowl for a centrifugal impeller 30 located between the walls 11 and 20 and in register with the outlet port 27.

The impeller 30 draws the air in the treatment chamber away from the openings 26, through the outlet port 27, and propels it at high velocity through the heating chamber, from which it returns to the treatment chamber through two inlet ports near the front wall thereof. These inlet ports are formed in the partition 24 and are located below but in register with the treatment stations established by the shoe-receiving openings 26. Each inlet port comprises a group of louvers 31 by which the air-stream is deflected away from the openings 26 and toward the rear wall of the treatment chamber. Moreover, the louvers are arranged to direct the air-stream against the linings of the lasting margins of pulled-over shoes inserted for treatment and supported in the position of the shoe 32 represented in Fig. 3.

A bracket 33 is provided to support the shoes for treatment. It comprises a vertically adjustable section 34 and a horizontally adjustable section 35 superposed on the latter. The section 35 has two arms 36 on which the heel parts of two shoes may lie.

The air-impeller 30 is affixed to the rotor shaft of an electric motor 40 (Fig. 3), the rear wall 11 having a small hole through which the shaft extends. The wall 13, curved as shown in Fig. 1, surrounds about three-fourths of the impeller and is merged with the wall 18 to direct the air-stream downward below the level of the treatment chamber 25.

The vertical web 22 of the heat-radiating member is hollow and contains two electric heating units 41 that stand upright in sockets. The heat generated by these units is radiated into the heating chamber by the web 22, the bottom wall 15, the partition walls 20 and 21, and the walls 13 and 18. The partition walls 20 and 21 also radiate heat into the treatment chamber, and the wall 21 conducts heat to the sheet metal partition 24 and to a sheet metal baffle wall 42 (Figs. 2 and 3). Heat is also conducted to the wall 42 by the bottom wall 15.

The web 22 constrains the air-stream to flow from right to left, the baffle wall 42 deflects it from left to right, and the walls 17 and 10 deflect it from right to left. In flowing past the two groups of baffle pins 23 the air traverses both sides of the wall 22 containing the heating units 41 and acquire a high temperature. The baffle wall 42 not only constrains the air-stream to traverse the second group of pins 23 but also causes it to follow a zigzag course under and in contact with the bottom wall 21, 24 of the treatment chamber.

Since the impeller 30 can deliver no more air

into the treatment chamber than it takes out through the port 27, no hot air is blown out through the shoe-receiving openings 26, but the total quantity is maintained in the closed air-circuit to conserve the heat and to be used repeatedly to treat the work and to carry moist vapor to the work.

Hot moist vapor is supplied to the air-stream through a duct 44 in the web 22, the emission port 45 of this duct being located in the heating chamber at the entering side of the first group of baffle-pins 23. The vapor is derived from a closed chamber in a generator 46 (Fig. 3) outside the air-circuit and located behind the rear wall 11. A pipe 47 conducts the vapor from the generator to the receiving end of the duct 44 in the top of the wall 20.

Water is supplied to the generator by a barometric feeder the reservoir of which is indicated at 48. The feed-pipe for water is indicated at 49. The generator comprises two electric heating units, one of which is indicated at 50 in Fig. 3. This one obscures the other which is located beside it. Both of these units may be used to start the supply of vapor and one of them may be used alone to continue the supply thereafter.

The water-seal maintained in the generator by the barometric feeder prevents the vapor from escaping except by flowing through the pipe 47 and the duct 44. The volume of vapor is small and the pressure thereof is negligible, but its temperature is raised as it flows through the duct 44. The superheated vapor discharged from the emission port 45 is absorbed and swept along by the air-stream, and the mixture of air and vapor traverses both sides of the heat-radiating web 22 and both groups of pins 23 before entering the treatment chamber 25 through the louvers 31. At this point the stream of air and vapor flows at high velocity toward the rear wall of the treatment chamber. If the forepart of a shoe is arranged to overhang the louvers as represented in Fig. 3 the lasting margin thereof will hang in the path of flow and receive the full force of the draft.

On the other hand, when the shoe is removed the vapor will be recirculated with the air-stream instead of escaping through the opening 26. Since the outer walls of the treatment chamber are thermally insulated, the heat radiated in that chamber by the inner walls or partitions is sufficient to prevent accumulation of condensate.

The elements above described are all supported by a frame 55 superposed on a stand or column 56. The reservoir 48, open at the bottom, stands in a basin 57. A post 58 affixed to the frame 55 supports the basin. A ledge 59 formed on the frame underlies and supports the casing of the air-circuit. The bracket 33 is affixed to this ledge.

Having thus described my invention what I claim as new and desire to secure by Letters Patent of the United States is:

1. A shoe-treating apparatus comprising outer walls and heat-radiating inner walls forming a closed air-circuit including a heating chamber and a treatment chamber in series, a power-driven blower arranged to circulate the air in said circuit, one of said inner walls being hollow and located in said heating chamber to be enveloped in the air-stream, heating means located inside said hollow wall, and means arranged to supply hot moist vapor, said hollow wall having a duct through which the vapor flows and from which it is emitted into the air-stream.

2. An apparatus as specified in claim 1 in which an inner wall integral with said hollow wall is arranged to radiate heat from one surface into said heating chamber and from another surface into said treatment chamber.
3. An apparatus as specified in claim 1 in which the emission end of said vapor-duct is located at a point from which the emitted vapor must traverse both sides of said hollow wall before entering said treatment chamber.
4. An apparatus as specified in claim 1 in which said heating chamber underlies said treatment chamber and in which one of said inner walls integral with said hollow wall is arranged to radiate heat into said treatment chamber.
5. An apparatus as specified in claim 1 in which the walls of said heating chamber are arranged to deflect the air-stream in a zigzag path under and in contact with the bottom wall of said treatment chamber.
6. An apparatus as defined in claim 1 in which said vapor-duct is arranged to receive vapor from a source outside said outer walls and superheat it before emitting it into the air-stream.
7. A shoe-treating apparatus comprising outer walls and heat-radiating inner walls forming a closed air-circuit including a heating chamber and a treatment chamber in series, the front wall of said treatment chamber having one or more shoe-receiving openings, the rear wall thereof 30
- 5 having an outlet port and the bottom wall thereof having one or more inlet ports arranged to direct the inflowing air against the work placed in said shoe-receiving openings, means for supplying hot moist vapor to said air-circuit, and a power-driven blower arranged to evacuate air from said treatment chamber through said outlet port and return it through said heating chamber and said one or more inlet ports.
- 10 8. An apparatus as specified in claim 7 in which said one or more inlet ports are provided with louvers arranged to deflect the air-stream away from said shoe-receiving openings and toward said rear wall.
- 15 9. A shoe-treating apparatus comprising means forming a closed air-circuit including a treatment chamber having a front wall, a rear wall and a bottom wall, said bottom wall having an inlet port to admit an air-stream, said front wall having a shoe-receiving opening arranged to locate a portion of a shoe in register with said inlet port, and said rear wall having an outlet port for the air-stream, a power-driven blower arranged to draw air from said chamber through said outlet port and return it through said inlet port, and means for supplying radiant heat and moist vapor to the air-stream flowing from said blower to said inlet port.
